(57) **CLAIM**

The ornamental design for shampoo bottle, as shown and described.

DESCRIPTION

FIG. 1 is a front elevational view of the design for shampoo bottle;

FIG. 2 is a rear elevational view of the design of FIG. 1;

FIG. 3 is a left side elevational view of the design of FIG. 1;

FIG. 4 is a right side elevational view of the design of FIG. 1;

FIG. 5 is a top plan view of the design of FIG. 1;

FIG. 6 is a bottom plan view of the design of FIG. 1;

FIG. 7 is a perspective view of the design of FIG. 1;

FIG. 8 is a front-elevational view of the design of FIG. 1; and,

FIG. 9 is an exploded perspective view of the design of FIG. 1, showing the cap removed from the bottle and showing the flip-top portion of the cap in an alternate position.

The broken line showing is for illustrative purposes only to show how multiple shampoo bottles fit together when placed adjacent to one another.
